UNITED STATES PATENT OFFICE.

GEORGE PRIFOLD, OF LINWOOD, PENNSYLVANIA, ASSIGNOR TO THE CONGOLEUM COMPANY, OF PHILADELPHIA, PENNSYLVANIA, A CORPORATION OF PENNSYLVANIA.

PRINTING-BLOCK FOR BLOCK-PRINTING MACHINES.

1,218,461.

Specification of Letters Patent.

Patented Mar. 6, 1917.

Application filed February 28, 1916. Serial No. 80,878.

To all whom it may concern:

Be it known that I, GEORGE PRIFOLD, a citizen of the United States, and a resident of Linwood, county of Delaware, State of Pennsylvania, have invented certain Improvements in Printing-Blocks for Block-Printing Machines, of which the following is a specification.

My invention relates to certain improvements in the blocks of a block printing machine particularly adapted for printing paint solutions on surfaces, such as oilcloth, linoleum and like material.

One object of my invention is to simplify the construction of the blocks of the block printing machine and to insure the proper and accurate transference of the paint compound from each block to the surface of the material being printed.

A further object of the invention is to design the block so that it will hold a given quantity of paint and while the block is rectangular in cross section it will make a circular deposit of paint on a prepared surface.

In the accompanying drawings:

Figure 1 is an inverted plan view of two sections of a printing block made in accordance with my invention;

Fig. 2 is a vertical sectional view of the same;

Fig. 3 is an enlarged inverted plan view of a section of the block;

Fig. 4 is an enlarged side view of the same;

Figs. 5, 6, and 7 are diagram views showing the method of applying the paint to the pins on the blocks and the transfer of the paint to the surface of the oilcloth, or other material, prepared to receive it;

Fig. 8 is a diagrammatic inverted plan view showing the pins and the area of the paint surface deposited by the pins;

Fig. 9 is an inverted perspective view of a section of a block showing the projecting pins;

Fig. 10 is a view of a portion of a printed surface showing the character of the paint deposits; and

Figs. 11, 12 and 13 are views illustrating modifications of the pins.

The usual practice of printing oilcloth is to use a block composed of a series of parallel ribs spaced a given distance apart and the design is formed by cutting away

a portion of these ribs so that the deposit of paint made by the blocks onto the surface of the oilcloth consists of a series of short and long lines. By my invention the pattern is made up of a series of circular deposits of paint evenly distributed over the surface and the pins are so arranged that the deposits substantially touch one another, as in the higher grades of this material it is desired to cover as much of the surface of the original material as possible and it is also essential that the deposits shall be uniform and that the continuity of the design shall be unbroken.

Referring to the drawings, 1 is a metallic plate. 2, 2 are the pins, which are integral with the plate and this plate is secured to the block 3 in any suitable manner. A number of these plates placed side by side form the printing block. It is the present practice to arrange the pins about twelve to the inch and the spaces between the pins equal their width. Each pin is preferably cruciform in cross section, as clearly shown in Figs. 3, 8, and 9, although it may be four-sided, and each side concaved, as in Fig. 11, or the pin may be made as in Fig. 12 in which there is a rectangular recess in each side. By forming the pins in this manner the paint applied to the ends of the pins, as in Fig. 5, will adhere to the sides thereof more readily than if the pins had flat sides. In order to strengthen the pins, I preferably taper them, as illustrated in Figs. 2 and 4, and it will be understood that they are cast of a composition resembling type metal. In making these pin plates a punch is used, which is of the exact shape of the pin and impressions are made in a wooden block, preferably bass wood, by heating the punch and burning the block to form a cavity of a given depth. These cavities are a given distance apart determined by the particular design it is desired to form. Then a casting is made, using the block as a mold. This is a comparatively cheap method of making a printing plate and the plates can be made a certain size and can be arranged side by side over the entire surface of the printing block, as in Fig. 1.

The entire design is formed when the impressions are made in the wooden blocks which form the molds so that the impressions of one block will have a given rela-

tion to the impressions in another block so that when the plates are cast from these blocks and are mounted on their respective printing blocks, one design will register 5 with another, and where the blocks are used for printing different colors, then one color will have a given relation to another.

In some instances, a pin having the shape illustrated in Fig. 13, may be used without 10 departing from my invention.

Referring now to Figs. 4 to 7, inclusive, the ends of the pins are supplied with paint from a roller 5, shown in Fig. 5, which rotates in a receptacle on a paint carriage of 15 the usual form. The paint will not only be deposited on the end of the block, but also on the sides, as indicated at *x*, so that when the carriage is withdrawn and the block is lowered to the depositing position, the 20 paint carried by the ends of the pins will be transferred onto the surface *y* of the material, Fig. 6, and when the pins are raised, as in Fig. 7, the paint will spread in circular form, as illustrated in dotted lines, Fig. 25 8, so that one deposit will come in close contact with an adjoining deposit, producing a surface effect clearly shown in Fig. 10. Where several colors are introduced, the 30 designs are so formed that one color will have a given relation to another color so as to completely cover the base material but, in some instances, where a limited number of colors is used and where the base coating is of a given color then the deposits on this 35 base may form outline designs. Although a rug of this type may have a passing effect, it does not possess the wearing qualities of one in which the entire surface has received a paint deposit.

40 I claim:

1. A printing pin for a block printing machine having a printing face and having recessed sides serving as a carrier for the printing composition.

2. A printing pin for a block printing 45 machine, said pin being substantially rectangular in cross-section and having a recess at each side serving as a carrier for the printing composition.

3. A printing pin for a block printing 50 machine, said pin being cruciform in cross-section to provide recesses in the sides which serve as a carrier for the printing composition.

4. A printing pin for a block printing 55 machine, said pin being cruciform in cross-section to provide recesses in the sides which serve as a carrier for the printing composition, said pin being tapered from the point to the butt.

5. A printing block for a block printing machine consisting of a plate having a series of integral pins spaced apart, each pin having recesses at the sides thereof 60 serving as a carrier for the printing composition, substantially as herein described.

6. A printing block for a block printing machine, consisting of a plate having impression pins cast integral therewith to form a design, the pins being evenly spaced 70 over the surface of the plate, the space between the pins being equal to the width of the pins so that when paint is applied to the ends of the pins and impressions are made on a material the deposits will be equally 75 distributed over the surface of the material, one deposit being located in close proximity to another deposit.

7. A printing block for a block printing machine, consisting of a series of cast plates 80 arranged side by side and secured to the block; a series of integral pins projecting from the plate, the pins being spaced apart, the spaces being substantially the width of the pins, each pin having recesses in its 85 sides and tapered from the point to the base.

GEORGE PRIFOLD.
